(57) **CLAIM**

We claim the ornamental design for an accessory mount, as shown and described.

DESCRIPTION

FIG. 1 is a perspective view of an accessory mount according to an embodiment of the invention.

FIG. 2 is a front view of the accessory mount of FIG. 1.

FIG. 3 is a rear view of the accessory mount of FIG. 1.

FIG. 4 is a first side view of the accessory mount of FIG. 1.

FIG. 5 is a second side view of the accessory mount of FIG. 1.

FIG. 6 is a top view of the accessory mount of FIG. 1; and, FIG. 7 is a bottom view of the accessory mount of FIG. 1. The portions of the accessory mount shown in broken lines are included for the purpose of illustrating environment and form no part of the claimed design. The portions of the accessory mount shown in broken lines having unequal length segments illustrate the boundary of the claimed design and form no part of the claimed design.

1 Claim, 5 Drawing Sheets
